FERDINAND MORA CANDA, OF NEW YORK, N. Y.,

ROLL FOR ROLLING MILLS.

1,427,063.

Specification of Letters Patent. Patented Aug. 22, 1922.

Application filed December 1, 1919. Serial No. 341,786.

To all whom it may concern:

Be it known that I, FERDINAND MORA CANDA, a citizen of the United States of America, and resident of the borough of 5 Manhattan, city, county, and State of New York, have invented a Roll for Rolling Mills, of which the following is a specification.

My invention relates to rolls for metal 10 rolling mills and the like, and comprises a grooved or ridged roll, the top portions of the ridges of which are formed of a metal which is harder than the body of the roll or roll-shell, and are held in place by being 15 shrunk on or forced on, and also, preferably, by being welded to the body of the roll or roll-shell, at their edges.

In the operation of rolling mills, one important feature in the cost of operation is, 20 the necessity for trueing the rolls. When the rolls require to be maintained in accurate shape, as, for example, when accurate rolling to a desired cross-section is required, the necessity for frequent trueing of the rolls 25 adds quite noticeably to the expense, and moreover causes considerable delay. In the case of rolls the ridges of which are required to be quite sharp, wear of these ridges is particularly undesirable.

30 In some cases the roll comprises a shell mounted upon a shaft or mandrel; while in other cases the roll is solid. In the former case the shell must be made of tough steel which cannot be very hard, else it is likely to 35 break, and in the latter case the entire roll must be of tough and, therefore, relatively soft steel. If the top portions of the ridges of these rolls may be separately formed, the durability of the roll as a whole is increased, 40 since it is these top portions which, mainly, are subject to wear; and if they may be removed or replaced, when badly worn, by so doing the roll is practically renewed. But if these top portions of the ridges may be 45 made of harder metal than the body of the roll or shell; for example, if these top portions may be formed of hard steel such as tool steel, or even air-hardening steel, then owing to the greater life of such hard portions, as 50 compared with similar portions formed of the same grade of steel as the body of the roll, obviously the roll need be trued only at relatively infrequent intervals, and its effective life up to the time when the top portions of the ridges require renewal, is very 55 greatly increased.

The object of my invention is to reduce the wear of ridged rolls such as referred to, and therefore to prolong the effective life of such rolls, and to render less frequent the necessary trueing thereof.

I will now proceed to describe my invention with reference to the accompanying drawing illustrating various embodiments thereof, and will then point out the novel features in claims: In said drawings:

Figure 1 is a more or less diagrammatic elevation and partial longitudinal section of a mill roll embodying my invention, and Figures 2-8 inclusive are similar fragmentary axial sections of various forms of rolls embodying my invention.

Referring now to the drawings, and first to Figure 1, numeral 1 designates a roll-shell mounted upon a shaft or mandrel 2 and driv- 75 ingly connected thereto by means of a key 3. 4—4 designate rings shrunk on to the shell 1 and constituting the top portions of the ridges of the roll. As shown, these ridge rings 4 are held in place not merely by 80 being shrunk on, but also in that they are provided in their bases with grooves 5 engaged by corresponding shoulders of the shell. However, this mechanical engagement of the ridge-rings and the shell is not 85 material to the invention, as the tight grip produced by the shrinking of the rings 4 on the shell will ordinarily be quite sufficient to hold the ridge-rings in place.

Obviously, various constructions whereby 90 these ridge-rings are interlocked with the roll body may be employed. In the construction shown in Figure 2 the base of each ridge-ring 4^a has the form of a very broad V.

With advantage, the union between the 95 body of the roll and the ridge-rings may be increased by welding at the contiguous edges. Figures 3 and 4 illustrate this welding, 6—6 designating strips of metal introduced by a familiar welding operation into 100 notches formed at the contiguous edges of the ridge-rings 4^b, 4^c and shell, and firmly welded to both the shell and the rings and so uniting the same to one another. So firmly do these welded-in rings 6 unite 105 the body of the roll to the ridge-ring, that these parts will be held together even should there be, in operation, sufficient local heating of the ridge-rings to expand them to a degree sufficient to neutralize or nearly neu- 110 tralize the previous shrinking.

The rolls shown in Figures 1-4 inclusive

are suitable for various purposes, for example are suitable for use in the ball rolling mills shown in my applications for Letters Patent Serial No. 329,774 filed October 10, 5 1919, Serial No. 332,284 filed October 21, 1919, Serial No. 334,030 filed October 28, 1919. Another type of roll to which my invention is well adapted is that intended for rolling angle bars, particularly the so-called "square root" angle bar. Figures 5, 10 6, 7 and 8 show rolls adapted for rolling such angle bars the forms of the ridge-rings, here designated by numerals 4^d, 4^e, 4^f and 4^g, respectively, being such as adapted for that purpose, and the base-forms and welding-strip arrangements being as described in connection with previous corresponding figures.

While the metal of the ridge-rings may 20 be of the same general character as that of the body of the roll, preferably such rings are formed of harder steel, for example tool steel or so-called air-hardening or self-hardening steel, or various of the suitable alloy 25 steels. Such hard steel rings will require trueing at relatively infrequent intervals only; and when worn past trueing, or when cracked or chipped or pitted, they may be removed readily and new rings substituted 30 for them, thus producing in effect, a new roll. It is a simple matter to take off a ring which is held in place by mere shrinking or by a force fit, and it is equally easy to remove rings held in place by welding, since 35 it is easy to cut out the welding strips.

It may be said that, in a broad or general

sense, the shrinking of ridge-tops on a roll body and the forcing by pressure of ridge-tops on to roll bodies, are equivalent methods. In both cases the ridge-top rings are 40 held in place by friction. When in addition they are welded in place, the welded union supplements the frictional union. In the construction shown in Figures 3 and 7 the ridge rings may have been applied either by 45 shrinking or by pressure, or by both shrinking and pressure, the welded unions shown supplementing the frictional unions thus produced. In the following claim, wherein it is specified that the top portions of the 50 ridges are held to the roll body by frictional union, it is intended that both a force-fit such as is produced by pressing the rings on and a fit such as is produced by shrinking the rings on shall be included. 55

What I claim is:

A rigid rolling mill roll, comprising a roll body having a series of contiguous grooves or troughs, and rings of harder steel shrunk thereon to constitute the ridges 60 which separate the grooves, said ridge rings having their sides conform to the slope of the adjacent grooves to thereby form continuations thereof.

In testimony whereof I have signed this 65 specification in the presence of two subscribing witnesses.

FERDINAND MORA CANDA.
